UNITED STATES PATENT OFFICE.

EMMA J. LAWRENCE, OF PHILADELPHIA, PENNSYLVANIA, ASSIGNOR TO
THE HARTLEY CARPET AND RUG COMPANY, OF SAME PLACE.

DESIGN FOR A RUG.

SPECIFICATION forming part of Design No. 16,820, dated July 27, 1886.

Application filed June 21, 1886. Serial No. 205,842. Term of patent 3½ years.

To all whom it may concern:

Be it known that I, EMMA J. LAWRENCE, a citizen of the United States, residing in Philadelphia, Pennsylvania, have invented a new 5 and original Design for Rugs, of which the following is a specification.

My design for a rug is fully shown in the accompanying photographic illustration of half the rug.

10 My design comprises a central portion, A, with a surrounding border, B, narrower at the sides than at the ends, the border being separated from the center piece by a narrow band, *a*, of bead-like ornamentation. The 15 center piece consists of a dark background, having representations of conventional flowers or blossoms on trailing vine-like stems extending over the background, and in the center is a circular-shaped ornament, *b*, with radiating 20 arms. The groundwork of the border B is made of a contrasting color from that of the center piece, and has vine-like leaves and flowers on this background. On the border, at the sides, there are conventional ornaments 25 *e* and *f*, the ornaments *e* being of an open-

fan shape and in alternately reverse position, while the ornaments *f*, of a crown shape, alternate with the ornaments *e*.

I claim—

1. The herein-described design for a rug, 30 comprising center piece and border, the center piece having flowers, while the border has leaves and flowers at the end and alternately reversed ornaments *e* and *f* at the sides, substantially as shown and set forth. 35

2. The herein-described design for a rug, comprising center piece and border, the center piece having a central ornament, *b*, and surrounding conventional flowers, while the border has leaves and flowers at the end and 40 alternating ornaments *e* and *f* at the sides, substantially as shown and set forth. 45

In testimony whereof I have signed my name to this specification in the presence of two subscribing witnesses.

EMMA J. LAWRENCE.
